DYEING MACHINE

Robert M. Bell, Ardsley, and George E. Horswood, Palmyra, Pa., assignors to Klauder Weldon Giles Machine Company, Philadelphia, Pa., a corporation of Delaware.

Filed July 31, 1961, Ser. No. 128,253
5 Claims. (Cl. 68—188)

This invention relates to skein dyeing machines.

In the art of dyeing yarns, the skeins are mounted on sticks which are suspended within a vat and means is provided for circulating the dyeing liquor around, and through, the yarn.

In order to prevent marking, it is necessary to minimize contact between the skeins and the skein-supporting stick and it is also necessary that the skeins be spaced from each other or arranged in an open pattern to permit free flow of the liquor between and through the skeins and thus insure uniform results.

It is therefore one object of the invention to produce an improved carrier in which the skeins are supported with minimum contact with their supports; in which the skeins are adequately spaced whereby the liquor circulates between and through, the skein.

Loading the skeins onto the supporting sticks and placing the sticks directly in the vat takes time, during which the vat is idle.

It is therefore a further object of the invention to produce an improved carrier which can be loaded and unloaded outside of the dye vat and which can be dropped into, and lifted from, the vat quickly and easily so as to reduce interruption of the operation to a minimum.

The full nature of the invention will be understood from the following specification and accompanying drawings in which:

FIG. 1 is an exploded, front elevational view of a skein carrier and dyeing vat embodying the invention.

FIG. 2 is an exploded, sectional view looking in the direction of line 2—2 on FIG. 1.

FIG. 3 is an exploded, sectional view on line 3—3 on FIG. 2.

FIG. 4 is a view, partly in vertical section and partly in front elevation, showing the carrier and vat of FIG. 3 in assembled position.

FIG. 5 is a horizontal, sectional view looking in the direction of line 5—5 on FIG. 4.

FIG. 6 is an enlarged, sectional view looking in the direction of line 6—6 on FIG. 2.

FIG. 7 is a horizontal, sectional view looking in the direction of line 7—7 on FIG. 6.

FIG. 8 is an enlarged, sectional view looking in the direction of line 8—8 on FIG. 6.

FIG. 9 is an enlarged, sectional view looking in the direction of line 9—9 on FIG. 7.

FIG. 10 is similar to FIG. 6, but showing another embodiment of the invention.

FIG. 11 is a horizontal, sectional view looking in the direction of line 11—11 on FIG. 10, showing the yarn-carrying sticks in one position thereof.

FIG. 12 is a vertical, sectional view looking in the direction of line 12—12 on FIG. 10.

FIG. 13 is similar to FIG. 11, but showing the yarn-carrying sticks in another position thereof.

A dyeing apparatus embodying the invention includes a vat 20 which is adapted to fit in an emplacement 22 having a drain 24. The vat is supplied with water and chemicals through pipe 26 and is emptied through drain 28.

The vat is divided by partition 30 into two compartments 32 and 34, the bottoms of which are formed by

2

screens 33 and 35, respectively. Below screens 33 and 35 is a heating coil 36 and an impeller 38 which is driven by pulley 40 which is driven by reversible motor M. When the impeller is rotated in one direction, the dyeing liquor is circulated in the direction of arrows 42, and vice versa.

The yarn carrier is formed of two sections, A and B, which are adapted to fit in vat compartments 32 and 34, respectively. Carrier sections A and B are formed of a common front wall 44, a common rear wall 45 and inner walls 46 and 47 which are spaced apart to form a channel 48 which is adapted to receive partition 30 when the carriers are lowered in the vat, as shown in FIG. 4. The bottoms of sections A and B are open and their tops are formed of screens 50 and 52. The opposite ends of carrier sections A and B are open and are provided with overhead sliding doors 54.

Carrier sections A and B are integral with each other and with a cover 56 which is provided with loop 58 for engagement with hook 59 of a lift, or overhead crane, not shown. By this arrangement, the yarn carriers and the cover form a rigid assembly which can be lifted from, or lowered into, the vat as a unit. When the carrier sections are lowered into the vat, their bottom edges come to rest on flexible gasket 59a to form a watertight seal. Also, when the parts are in this position, flange 60 of the cover comes to rest on rim 61 to close the top of the vat. It will also be noted that the cover is raised above screens 50 and 52 and is preferably domed so that, when it is in the vat closing position of FIG. 4, a passage 62 is provided to permit liquor in one of the compartments, such as compartment 32, to flow upwardly through screens 33 and 50, then horizontally through passage 62, then downwardly through screen 52 and 35 and finally upwardly through screen 33 to complete the cycle, as indicated by arrows 42 in FIG. 4.

In both embodiments, the skeins of yarn are supported on sticks which have only line contact with the skeins. To this end, the skein-supporting sticks have a cross-section, such as that shown in FIG. 9, from which it will be seen that upper divergent edges 64 support the skein and that they co-operate with lower divergent edges 66 to keep the skein open to permit free circulation of the dyeing liquor around and through the skein, as shown by the arrows in FIG. 9.

Also in both embodiments, the sticks which support the yarn are automatically uniformly spaced to provide clearance between adjacent skeins.

In one embodiment, the skeins are suspended from the sticks 68, each of which is provided with an enlarged head 70 which may be solid, or which may be in the form of a hollow frame as long as the width of the head, as viewed in FIG. 7; that is, the distance between sides 72 thereof is at least equal to the greatest width of the skeins supported by the sticks so that if the sticks are laid side by side, with the sides 72 of their respective heads touching, the skeins carried by adjacent sticks will be spaced as shown in FIG. 7.

When sticks 68 are used, the front and rear walls, 44 and 45, of the compartments are provided with upper shelves 74 to receive the heads 70 of the sticks from which the skeins are suspended. To load a carrier section, it is merely necessary to place the sticks, successively, on the outer ends of the shelves and to push them inwardly, or in the direction of arrows 78, until the head of the innermost sticks abuts the inner wall 46 or 47 of the compartment. See FIGS. 1, 6, 7 and 8.

Instead of sticks 68, we may use sticks 80 which have the same cross-section as sticks 68, but which have flattened ends, as shown in FIGS. 10—13. When sticks 80 are used, shelves 74 and 76 are replaced by openings 84 and 86

which are formed in fixed liners 87. It will be seen from FIG. 12 that openings 86 are deeper than openings 84 and that the distance between wall 44 and 45 is greater than the length of sticks 80. In this construction, there is also provided a slide 88 which is movable relative to wall 45 and has openings 90 which correspond to openings 86. To insert sticks 80, slide 88 is moved until its openings 90 register with openings 86. Sticks 80 are now inserted as far as they will go through openings 86, as shown in solid lines at the top of FIG. 12, and are then moved through openings 84 as far as they will go, as shown at the bottom of FIG. 12. With all of the sticks in their extreme right-hand position, slide 88 is moved to bring solid portions 92 thereof into registration with openings 86, thus locking stick 80 against lateral movement.

The yarn tends to shrink and to control shrinkage, we provide lower shelves 76 for receiving sticks 68 or 80 which engage the lower ends of the skeins, as best shown in FIGS. 2 and 3. It will be noted that there are a number of vertically spaced upper and lower shelves 74 and 76 so as to accommodate skeins of various lengths and so as to provide for a wide range of shrinkage control.

It will be noted that, once the doors are closed, sticks 68, the outermost of which will abut the inside of the doors, will be locked against movement and that when sticks 80 are used, the outer ends of slides 88 will abut the inside of the door and will be locked against any movement.

What we claim is:

1. A dyeing machine including a vat having an open top, a yarn carrier adapted to nest within said vat and having an open bottom, a gasket located at the bottom internal periphery of said vat and on which the bottom edge of said carrier rests when said carrier is nested within said vat, a partition dividing said vat into two sections, and a hollow mullion dividing said carrier into two sections and adapted to receive said partition when said carrier is lowered into said vat.

2. The structure recited in claim 1 in which the top and bottom of said carrier are open, and a first screen

disposed across the top of said carrier and a second screen disposed across the bottom of said vat.

3. The structure recited in claim 1 in which one end of said carrier is open, and shelves carried by said carrier and accessible through said open end, skein-carrying sticks substantially co-extensive with the interior of said carrier with their opposite ends resting on said shelves, and means for automatically spacing said sticks in a predetermined order.

10 4. A dyeing apparatus including a vat, a yarn carrier, opposed shelves in said carrier, skein-supporting sticks insertable into said carrier with their opposite ends resting on said shelves, each of said sticks having horizontally pairs of spaced upper and lower knife edges for providing 15 line contact supports for said skeins, the ends of said sticks being of a greater horizontal cross section than the intermediate bodies thereof whereby, when the ends of adjacent sticks abut each other, the bodies of said sticks will be spaced apart to accommodate the skeins 20 suspended therefrom.

5 5. The structure recited in claim 4 and openings formed in the opposite walls of said carrier for receiving the 25 opposite ends of said sticks, the openings in one of said walls being deeper than the opening in the other of said walls, and a slide having spaced openings therein and movable to first position in which the openings in said slide register with the openings in one of said walls and to a second position in which the openings in said slide are out of registration with the openings in said one wall.
